UNITED STATES PATENT OFFICE

GEORGE E. NERNEY, OF ATTLEBORO, MASSACHUSETTS.

DESIGN FOR A HANDLE FOR SPOONS, FORKS, OR SIMILAR ARTICLES.

41,739.

Specification for Design.

Patented Sept. 5, 1911.

Application filed May 22, 1911. Serial No. 628,860. Term of patent 7 years.

To all whom it may concern:

Be it known that I, GEORGE E. NERNEY, a citizen of the United States, residing at Attleboro, in the county of Bristol and State of Massachusetts, have invented a new, original, and ornamental Design for a Handle for a Spoon, Fork, or Similar Article, of which the following is a specification, reference being had to the accompanying drawing, forming part thereof.

The figure is a plan view of a handle for

a spoon, fork or similar article, showing my new design, for use for a handle for a spoon, fork, or similar article.

I claim:

The ornamental design for a handle for a spoon, fork or similar article as shown.

GEO. E. NERNEY.

Witnesses:

R. C. THOMPSON,
EFFIE R. CRUMLEY.
